Da-Lite Screen Company, Inc., Chicago, Ill., a
corporation of Illinois

Application March 15, 1951, Serial No. 215,818

13 Claims. (Cl. 160—24)

1

The main objects of this invention are to provide an improved stand structure for portable picture screens, particularly with respect to simplifying the operations of setting up the screen for use and retracting its parts into compact form for transportation and storage; to provide improved latching structures for releasably locking the parts in various positions; and to provide specific improvements in the structure of screens of the type generally disclosed in the patent of J. T. Heck No. 2,355,799 issued August 15, 1944, and the patent to Leo J. DuMais No. 2,370,235 issued February 27, 1945.

A specific embodiment, showing this invention is shown in the accompanying drawings in which:

Figure 1 is a perspective view of the screen structure as it appears with its tripod legs in position for supporting the standard in an upright position and with its screen secured in parallel relation to the standard.

Fig. 2 is a fragmentary detail, partly in section, as viewed from the line 2—2 of Fig. 1.

Fig. 3 is a section taken on the line 3—3 of Fig. 2 of the latch mechanism that locks the extension rod in various positions.

Fig. 4 is a detail of the extension rod on a reduced scale and showing its latching apertures.

Fig. 5 is a fragmentary detail showing the relation of the tripod legs to the main standard and to the latching mechanism for securing the legs in their folded relation to the standard.

Fig. 6 is a further detail in perspective of parts of the latch mechanism shown in Fig. 5.

Fig. 7 is a perspective view of the same showing its relation to the hinge fitting to which are pivotally connected the links that brace the legs of the tripod in their expended load-carrying position.

Fig. 8 is a sectional view of the same parts in their relation to the spring that lifts the extension rod away from its case-locking position and the spring that controls the latch member that locks the legs in their folded position.

Fig. 9 is a detail taken on the line 9—9 of Fig. 8.

Fig. 10 is a fragmentary sectional detail showing the relation of the tripod legs to their slideable hinge member and to their bracing links and springs.

Fig. 11 is a detail in perspective of the slideable hinge member.

Fig. 12 is a fragmentary detail of the screen case and screen bail.

In the form shown in the drawings, the main standard 11 is in the form of a tube adapted

5 to be supported in an upright position by tripod legs 12. The screen case 13 is pivoted at 14 to a bracket member 15 that is provided with a handle 16 and slidably mounted on the standard 11 where it is locked in various positions of adjustment under control of a latch button 17 by latch mechanism of suitable form not involved in the present invention. A stop 18 establishes the downward limit of movement of the bracket 15 with respect to the standard 11.

10 As shown in Fig. 1, the legs 12 of the tripod are pivotally connected at their upper ends to a sleeve or slideable fitting 19 by pivot pins 20 and are also connected to a fitting 21 that is 15 fast on the lower end of the standard 11 by means of links 22. These links are pivoted to wings 23 on the fittings 21 by pivots 24 and are also pivoted at their other ends, by pins 25, to their respective tripod legs 12.

20 A wire spring 26 is wound helically around each pin 25 and has arms at its ends bearing between link 22 and leg 12 in such manner as to normally urge the tripod leg to its limit of outward movement on the hinge pin 20.

25 In the form shown, the tripod legs are of channel-shaped section and the fitting 19 has wing structures that fit within the bosom of the channel and have stop surfaces 27 that limit the outward movements of the legs 12 on their pivots 28 and thus limit the downward sliding movement 30 of the fitting 19 on the standard 11.

35 Each leg 12 of the tripod has a latch shoulder in the form of a pin 28 extending across the space between the side flanges of the channel-shaped leg and positioned to engage latch lug 29 on a spider arm 30 of a latch member 31. The latch member 31 is carried by a stem 32 which is vertically slidable in a cap fitting 33 that is fastened to the lower end of the standard tube 11 by a screw 34. The stem 32 is of square or other suitable cross section so as to be non-rotatable and is located on the fitting 33 so as to be vertically slidable along the axis of the standard 11.

40 A helical compression spring 35 surrounds the stem 32 and bears between a shoulder 36 in the form of a washer at the top of the stem 32 and fitting 33 so as normally to urge the latch member 31 toward the position in which its lugs 29 hookingly engage the latch pins 28 of the tripod legs 12 when they are folded against the standard 11. The cap member 33 also serves as an abutment for a helical compression spring 37 that engages the guide shoe 38 on the lower end of an extension rod 39 that is telescopingly

slidable within the standard tube 11. An annular wall 49 welded on the fitting 33 separates the adjacent convolutions of the springs 35 and 37 so as to avoid interference between them. A lever 41 in the form of a plate interposed between the latch member 31 and the cap fitting 33 is fulcrumed at 42 on the fitting 33 and has a button 43 at its operating end. The lever 41 has an aperture 44 through which the stem 32 passes and has a bifurcated arm 45 that is bent upward to straddle one of the wings 23 of the fitting 21 so as to prevent lateral displacement of the lever 41.

The extension rod 39, as shown in Fig. 2, is slidably mounted in a cap fitting 46 at the upper end of the standard 11 and has a bracket 47 mounted on its upper end which has an arm shaped to form a hook 48 for receiving the bail 48.1 (Fig. 12), by means of which the end latch 48.2 of the screen is hung upon the extension rod 39 when the screen 48.3 is in use. The bracket 47 also has a depending lug 49 positioned to engage an aperture 50 in the end cap 51 of the screen case 13. The upper surface of the cap 51 has a depression, indicated by dotted line 52 in Fig. 2, in which the bracket arm 47 is nested when the pin 49 is in engagement with the aperture 50.

The cap 46 at the upper end of the main standard 11 houses a latch mechanism comprising a latch pin 53 positioned to engage a series of apertures 54 in the front wall of the extension rod 39 for locking the extension rod in various positions of longitudinal adjustment with respect to the standard 11. As shown in Fig. 3, the pin 53 is carried by a slide member 55 that comprises a pair of side arms 56 extending across opposite sides of the extension rod 39, which arms are seated in registering slots formed in the cap 46 and the upper end of the standard 11. A compression spring 57 normally urges the slide member 55 toward the right of Fig. 3. The right-hand end of the member 55 is finished with an ornamental push button 58, whereby the pin 53 is withdrawn from the aperture 54 by an inward pressure upon the button 58 against the action of the spring 57.

The various parts of the screen stand are so proportioned that when the screen-case-carrying bracket 15 is in its lowermost position, as represented by the stop 18 in Fig. 1, and the case is turned in parallel relation to the standard 11, then when the extension rod 39 is pushed inwardly into the standard 11 to the limit of its movement, as indicated by full lines in Fig. 2, its lug 49 will lock the case against swinging on its pivot 14. The uppermost one of the apertures 54 in the extension rod 39 is located so as to be engaged by the latch pin 53 to lock the extension rod in this position. The lower end cap 38 on the rod 39 at such time compresses the spring 37, so that when the push button 58 is pressed to release the pin 53 from the respective aperture 54, the extension rod 39 will be lifted by spring 37 to the position shown in broken lines in Fig. 2 and will release the screen case so that it may be swung to its horizontal position with respect to the standard.

The sliding fitting 19 to which the tripod legs are hinged is provided with a projecting lip on one side that forms a finger-hold 59. When the parts are in the position in which they are shown in Fig. 1, the operator need only lift on the finger-hold 59 to collapse the legs of the tripod against the sides of the standard 11. A quick

movement of this kind causes the latch pins 28 on the legs 12 to ride up over the beveled ends of the latch lugs 29 of the latch member 31 by which the legs 12 are locked against spreading. At this time, the parts of the stand are in their most compactly compressed position with the handle 16 in appropriate location for carrying the screen stand when tilted to a horizontal position.

In order to set up the screen for use, it is only necessary for the operator to depress the lever button 43 to shift the latch member 31 out of engagement with the pins 28 whereupon the springs 26 will throw the tripod legs 12 apart to the position in which they are shown in Fig. 1. Then the operator, by pressing the latch button 58, causes the latch pin 53 to withdraw from engagement with rod 39 and the spring 37 lifts the rod 39 to the position in which it is shown in broken lines in Fig. 2, thus allowing the case 13 to be swung to its horizontal position.

The bail 48.1 on the end latch 48.2 of the screen is then used to withdraw the screen 48.3 from its housing case until the bail can be hung on the hook 48. Then while pressing the button 58 to retract the latch pin 53 from the rod 39, said extension rod can be released and shifted to any desired position at which pin 53 will engage one of the apertures 54, as will be understood.

Although but one specific embodiment of this invention is herein shown and described, it will be understood that numerous details of the structure shown may be altered or omitted without departing from the spirit of the invention as defined by the following claims.

We claim:

1. A portable screen stand, comprising a tubular standard, an extension rod telescoping therein, a screen reel case pivotally mounted on said standard, a bracket arm mounted on the free end portion of said extension rod, means for interlocking said bracket arm and one end of said case when said case is in approximately parallel relation to said standard said extension rod being depressable into said standard, a spring normally urging said extension rod outward from such depressed position, latch means acting between said standard and said extension rod to secure the rod in such depressed position, a tripod connected to one end of said standard and having legs foldable against said standard, and spring-pressed latch means acting between said standard and tripod to hold the legs folded against said standard.

2. A portable screen stand, comprising a tubular standard, an extension rod telescoping therein, a screen reel case pivotally mounted on said standard, a bracket arm mounted on the free end portion of said extension rod, means for interlocking said bracket arm and one end of said case when said case is in approximately parallel relation to said standard and said extension rod being depressable into said standard, a spring normally urging said extension rod outward from such depressed position, latch means acting between said standard and said extension rod to secure the rod in such depressed position, a tripod connected to one end of said standard and having legs foldable against said standard, spring means normally urging said tripod legs apart to their load-carrying relation to the standard, and spring-pressed latch means on the lower end of said standard acting between said standard and

tripod to hold the legs folded against said standard.

3. A portable screen stand, comprising a tubular standard, an extension rod telescoping therein, a screen reel case pivotally mounted on said standard, a bracket arm mounted on the free end portion of said extension rod, means for interlocking said bracket arm and one end of said case when said case is in approximately parallel relation to said standard and said extension rod being depressable into said standard, a spring normally urging said extension rod outward from such depressed position, latch means acting between said standard and said extension rod to secure the rod in such depressed position, a tripod connected to one end of said standard and having legs foldable against said standard, spring means normally urging said tripod legs apart to their load-carrying relation to the standard, latch means acting between said standard and tripod to hold the legs folded against said standard, said last-named latch means comprising individual latch shoulders on said legs and a latch member shiftably mounted on said standard for movement into and out of latching engagement with said shoulders when said legs lie against said standard, and spring means normally urging said latch member into position for latching engagement with said shoulders.

4. A portable screen stand, comprising a tubular standard, an extension rod telescoping therein, a screen reel case pivotally mounted on said standard, a bracket arm mounted on the free end portion of said extension rod, means for interlocking said bracket arm and one end of said case when said case is in approximately parallel relation to said standard and said extension rod being depressable into said standard, a spring normally urging said extension rod outward from such depressed position, latch means acting between said standard and said extension rod to secure the rod in such depressed position, a tripod connected to one end of said standard and having legs foldable against said standard, spring means normally urging said tripod legs apart to their load-carrying relation to the standard, latch means acting between said standard and tripod to hold the legs folded against said standard, said last-named latch means comprising individual latch shoulders on said legs and a latch member shiftably mounted on said standard for movement into and out of latching engagement with said shoulders when said legs lie against said standard, and spring means normally urging said latch member into position for latching engagement with said shoulders, and a trip lever coacting with said standard and latch member for shifting the latter out of such latching engagement.

5. A portable screen stand, comprising a tubular standard, a tripod connected to one end of said standard and having legs pivotally foldable against said standard, spring means normally urging said legs away from said standard, an extension rod telescoping into said standard at the end thereof that is distant from said tripod, a screen reel case pivotally mounted on said standard, a bracket arm on the outer end of said extension rod, means for interlocking said bracket arm and one end of said case when said case is substantially parallel with said standard and said extension rod is retracted into said standard, latch means acting between said standard and said extension rod to secure said exten-

sion rod in such retracted position, a fitting attached to the tripod bearing end of said standard, a compression spring seated on said fitting and normally urging said extension rod outward from its said retracted position, a bore in said fitting extending axially of said standard, a stem slidably through said bore, a latch member fast on the outer end of said stem, and having radially directed arms, coacting latch shoulders on said arms and respective legs of said tripod adapted to be interlocked and disengaged through axial shifting of said stem, a compression spring bearing between said fitting and stem to normally urge said stem to a position for engaging said coacting latch shoulders, and a lever acting between said fitting and latch member to separate said coacting latch shoulders.

6. In a portable screen stand, a standard, a plurality of legs hinged on said standard to swing from positions parallel to said standard to relative positions for supporting said standard in an upright position, springs normally urging said legs to such standard supporting positions, and latch means normally urged to engage said legs to hold them in their parallel positions.

7. In a portable screen stand, a standard, a fitting fixed at one end of said standard, a second fitting slidable along said standard, a plurality of legs hinged to one of said fittings and adapted to be swung between positions of substantial parallelism with said standard and relatively expanded positions for supporting said standard in an upright position, links respectively connecting each of said legs to the other of said fittings, spring means normally urging said legs apart, and latch means normally urged to engage said legs to hold them in their parallel positions.

8. The combination of claim 7, wherein the leg-latching means is mounted on the lower end of the standard.

9. In a portable screen stand, a standard, a fitting fixed at one end of said standard, a second fitting slidable along said standard, a plurality of legs hinged to said slidable fitting and adapted to be swung between positions of substantial parallelism with said standard and relatively expanded positions for supporting said standard in an upright position, links respectively connecting each of said legs to said fixed fitting, spring means normally urging said legs apart, transverse latch shoulders on said legs, a latch member slidably mounted on said standard to engage and disengage said latch shoulders, and a spring normally urging said latch member into position for engaging said latch shoulders.

10. In a portable screen stand, a standard, a fitting fixed at one end of said standard, a second fitting slidable along said standard, a plurality of legs hinged to said slidable fitting and adapted to be swung between positions of substantial parallelism with said standard and relatively expanded positions for supporting said standard in an upright position, links respectively connecting each of said legs to said fixed fitting, spring means normally urging said legs apart, transverse latch shoulders on said legs adjacent the lower end of said standard when said legs are in their parallel relation to said standard, and latch assemblage comprising a cap on said standard, a stem extending slidably through said cap axially of said standard, a latch member carried by said stem and having hook-shaped pawls for engaging the respective latch shoulders on said legs, a compression spring bearing between said stem and cap to normally hold said pawls into position to

engage said latch shoulders, and a lever bearing between said cap and latch member to oppose said compression spring and release said pawls from said shoulders.

11. A portable screen stand, comprising a tubular standard, an extension rod telescoping therein, legs pivotally mounted on said standard to swing between positions of parallelism with said standard to expanded positions for supporting said standard in an upright position, latch shoulders on each of said legs, a cap on the lower end of said standard, a stem extending slidably through said cap axially of said standard, a latch member carried by said stem and having hook-shaped pawls for engaging the respective latch shoulders on said legs, a compression spring bearing between said stem and cap to normally hold said pawls into position to engage said latch shoulders, a compression spring bearing between said cap and said extension rod to normally urge the latter upward from said standard, and latch means acting between said standard and extension rod to hold same depressed against the action of said last-named compression spring.

12. In a device of the class described, a standard, a collapsible tripod stand, a fitting on said standard slidable therealong, the upper ends of said stand pivotally secured to said fitting, a stationary fitting rigidly secured to the lower end of

said standard, link arms pivotally secured at one end to said stationary fitting and pivotally secured at their opposite end to said stand intermediate the ends thereof, latch means associated with said stationary fitting having radially extending fingers for cooperatively grasping and holding said stand in snug parallel position relative to said standard.

13. The device according to claim 12, wherein said latch means includes an axially disposed member telescopingly fitted in the lower end of said standard and also provided with a simple lever disposed between said fingers and said stationary fitting whereby movement of said lever causes said fingers and axial member to move vertically.
